INVENTOR
Raymond S. Huss.

BY
Joshua R. H. H. S.
ATTORNEY

UNITED STATES PATENT OFFICE

RAYMOND S. HUSS, OF CYNWYD, PENNSYLVANIA

INKWELL

Application filed March 3, 1930. Serial No. 432,590.

This invention relates to inkwells and has for an object to provide an inkwell of new and improved construction with new and improved means for closing the receptacle 5 against dirt and evaporation and with new and improved means for holding the pen when not in use.

A further object of the invention is to provide an inkwell, the receptacle of which 10 has an open upper side with a ball properly proportioned to close the opening and new and improved means for guiding and retaining the ball when moved by the insertion of a pen.

15 A further object of the invention is to provide an inkwell having a receptacle with an open upper side, a ball provided for closing the opening, a new and improved type of guide for retaining the ball in position and 20 returning it to closed position when a pen has been inserted and removed, and new and improved means for holding the pen when not in use.

With these and other objects in view, the 25 invention comprises certain novel parts, elements, units, constructions and functions as disclosed in the drawings, together with equivalents thereof as will be hereinafter more fully described and claimed.

30 In the drawings:

Figure 1 is a view of the improved inkwell in side elevation,

35 Figure 2 is a view of the improved inkwell in front elevation, as seen along arrow 2 at Figure 1,

Figure 3 is a top plan view of the improved inkwell,

Figure 4 is a sectional view of a modified type of support for the pen holder,

40 Figure 5 is a transverse sectional view through the pen socket taken on line 5—5 of Figure 1, and on an enlarged scale, and

Figure 6 is a sectional view taken on line 6—6 of Figure 5 on a still larger scale.

45 Like characters of reference indicate corresponding parts throughout the several views.

The improved inkwell which forms the subject matter of this application comprises a base 10 of any approved type, form or ma-

terial and the showing of the base as circular or of any other contour is to be considered as no limitation upon the invention.

Within the base 10 the receptacle 11 is provided and a limiting of this receptacle to a minor portion of the base is merely a matter of choice and the receptacle may be increased or decreased as found necessary or desirable.

The receptacle 11 has an opening in its upper side at 12 and a ball 13 is provided to fit into this opening and close the opening against the introduction of dirt or against evaporation.

Upon one side of the base an enlargement 14 is formed and again the exact formation of this feature is wholly immaterial and may be wholly omitted.

This enlargement 14, if employed as shown in the drawings or its equivalent, carries a spoon shaped guide 15 contoured to permit the rolling of the ball 13 thereunder by providing also means to prevent lateral movement of the ball, holding the ball always in operative position but always in view laterally under the spoon.

This guide 15 may be secured in any approved manner and showing fastening members 16 it is intended as no limitation, but merely as by way of illustration.

The enlargement 14, or any part of the base similarly located, is provided with means for holding the pen holder when not in use, here shown as sockets 17, into which the pen is thrust, as indicated at Figure 1.

At Figure 4 a modification is shown in that the pen supporting member is formed independently of the enlargement 14 and may be, as illustrated, formed integral with the guide member 15 and secured by the same securing means. This type of pen supporting device 18 is shown as secured upon the top of the enlargement 14.

The pen socket 17 is provided intermediate its ends with a groove 21 and into this groove is expanded a resilient open ring 22. The ring 22 is greater in its outside diameter than the interior diameter of the socket 17 and lesser in diameter than the diameter of the groove 21, so that it is held against displacement in

the groove while permitting expansion when the pen is inserted. This tends to retain the pen more firmly in the socket 17.

In operation the pen, if supported in the supporting sockets 17 or the applied socket 18, is withdrawn from the socket and thrust under the forward or outer perimetrical surface of the ball 13. This pushes the ball backwardly under the guide 15.

10 When the pen has been removed the ball returns to position, by rolling under the guide 15.

The expression used herein of a receptacle with an open top or an opening in the top 15 of the receptacle is to be also considered as having reference to a completely open receptacle with the pen opening formed only through the base into the receptacle and the terms employed of closing the receptacle are 20 to be construed as referring also to closing the receptacle by the mere closing of the opening in the base over the receptacle.

The invention is hereby claimed as follows:

1. An inkwell comprising a base having a 25 receptacle therein with an open top, a ball properly positioned to close the opening in the receptacle, and a spoon shaped guide tending to prevent displacement of the ball and to return the ball to closing position.

2. An inkwell comprising a base having a receptacle therein with an open top, a ball proportioned to close the opening in the top, a spoon shaped guide adjacent the opening enclosing the upper segment of and adapted 35 to guide the ball to closing position, and means to prevent displacement of the ball relative to the spoon.

3. An inkwell comprising a base having an 40 enlargement thereon with pen receiving sockets therein, said base being also provided with a receptacle with an open top, a ball properly proportioned to close the opening, and a spoon shaped guide member carried by the enlargement positioned to enclose the upper segment 45 of and prevent displacement of the ball and to guide the ball to closing position.

In testimony whereof I have signed my name to this specification.

RAYMOND S. HUSS.
